(57) **CLAIM**

The ornamental design for a shoe horn long handle as shown and described.

DESCRIPTION

FIG. 1 is a perspective view of a shoe horn long handle showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is an enlarged top plan view thereof;

FIG. 8 is an enlarged bottom plan view thereof;

FIG. 9 is a partial enlarged view of portion 9 in FIG. 1;

FIG. 10 is a partial enlarged view of portion 10 in FIG. 1;

FIG. 11 is a partial enlarged view of portion 11 in FIG. 2;

FIG. 11 is a partial enlarged view of portion 11 in FIG. 2;

FIG. 13 is a perspective view shown in another state; and, FIG. 14 is a perspective view of a shoe horn long handle showing my new design, in a split state.

The broken lines depict portions of the shoe horn long handle and form no part of the claimed design.

The dot dash line is included for the purpose of illustrating the bounds of the enlarged view and forms no part of the claimed design.
